FLOATING BODY GAME APPARATUS

Ralph Dawson Young, Morden, England

Application September 18, 1945, Serial No. 617,086
In Great Britain October 25, 1944

5 Claims. (Cl. 273—138)

1

This invention relates to surface tensioning devices and has for its object to provide improvements therein.

In accordance with the present invention from one aspect I provide game apparatus comprising: (a) a vessel containing liquid; (b) a floating body of thin flat form with means at one end to be engaged by a manually actuated boat-hook or the like enabling the body to be drawn across the water, and having; (c) an upstanding member at the other end of the floating body sufficiently high to cause surface tension to attract a second floating body and (d) one or more secondary floating bodies adapted to adhere to the first by surface tension. I provide a secondary floating body which may have an upstanding portion at one end for accentuating the action of surface tension thereon.

The accompanying drawings illustrate the invention as applied to games, wherein:

Fig. 1 is a plan of a tray adapted for playing one form of game.

Fig. 2 is a plan of one form of tug for use in connection with the tray illustrated in Fig. 1.

Fig. 3 is a side elevation of such a tug.

Fig. 4 is a plan of one form of barge for use in connection with the tray illustrated in Fig. 1, and Fig. 5 is a side elevation of such a barge.

Fig. 6 is a side elevation of a boat-hook for use in connection with the game illustrated in Figs. 1 to 4.

Fig. 7 is a plan of a tray adapted for playing a modified form of game.

Fig. 8 is a plan of a boat for use in connection with the board illustrated in Fig. 7.

Fig. 9 is a side elevation of such a boat.

Fig. 10 is a plan of a fish for use in connection with the tray illustrated in Fig. 7.

Fig. 11 is a side elevation of such a fish.

Fig. 12 is a plan of a modified form of tray.

In Figs. 1 to 6 I provide a water-tight tray *a* with vertical sides *b* and in this tray I provide two pairs, each of two movable walls *c* made of flat sided pieces and pivoted at *d* and a centre wall *w*. I also provide a thin flat member *e* of celluloid to represent a tug. The hull of the tug is flat and is pierced through the bow at *f*, and is provided with lateral projections *g* to represent paddles, and with a vertical stern and an upright stern post *h* in the middle of the stern. I also provide three members *i* representing barges, each barge comprising a flat hull with a rounded bow *j* and a straight stern *k* rounded at the corners. The stern post *l* and the stem *m* of each barge rise vertically from the hull. I also provide a

boat hook *o* or rod made of wire with a handle *p* at one end, and a lateral bend *q* at the other end, the wire being of such diameter as just to pass through the hole *f* in the hull of the tug.

In playing the game with two competitors a layer of water is placed in the tray *a*. The walls *c* are also placed parallel in the tray *a* with reference to the related centre wall *w* to form the banks of the canal at such a distance apart that the tug *e* will just pass between the walls *c* and *w* with a little room on each side. The tug *e* and the barges *i* are placed in the water in the tray. The skipper of the tug *e* then passes his rod *o* through the bow of the tug *e* and manipulates the tug by bringing it just close enough to a barge *i* for the surface tension created between the tug *e* and the water and the barge *i* and the water to attract the barge *i* to the tug *e* so that the stem *m* of the barge makes contact with the stern post *h* of the tug. The force which urges the tug *e* and the barge *i* together is the surface tension existing between the upright stern post *h* on the tug *e* and the water on the one hand and the upright stem *m* of the barge *i* on the other hand. When the stern of the tug is brought sufficiently near to the bow of the barge, the barge is attracted towards the tug. When the skipper of each tug has gotten one barge in tow his job is then to attach the second barge to the first and this he has to do by so manipulating the tug and the barge it is towing towards the stem of another barge. The water causes this free barge to move towards the barge already in tow so that the stem on the free barge is attracted and makes contact with the stern post of the barge in tow.

The skipper then has to get the remaining barge or barges in tow. He then must, by means of the rod, draw his barges between the canal banks formed by either of the two walls *c* and the centre wall *w* without the tug losing any of its barges. It will be found that the narrower the channel the greater the surface tension which tends to separate the tug and the barges. By graduating the distance from one to another of the members *c* and *w* forming the banks of the canal, the strength of the surface tension can be made to vary at different parts of the canal and this will introduce further difficulties or further ease in getting the tug to tow its barges through the canal without loss. The skipper who gets all his barges home first wins.

In a modified form of arrangement the device may be used with a timing arrangement, for example the wire wall members may be wire and may each be pivoted about the central point of

its base and by means of clockwork or other mechanism these members may be caused to rock about their pivots in a pre-arranged time.

If water or liquid be placed in the tray and the flat floating member be arranged within the narrow channel formed on the surface of the water by the wire wall members it will be found that for any given inclination of the wall members relative to each other the same floating member will always take the same time to traverse the length of the channel under the influence of the surface tension, the direction of travel being from the narrow portion of the channel towards the broader one. At the ends of its path or at intermediate places the floating member may be caused to operate switches or to act as an electric conductor to turn on lights and this arrangement may be used for advertising devices or for other arrangements in which timing is desired.

The grid formation of wire wall members reduces disturbance of the water surface when moving the walls.

The surface tension is also reduced by companion with a solid wall, but this has no serious effect.

As illustrated in Figs. 7 to 11 I provide a metal watertight tray *a'* of square shape and with upright edges or walls *b'*. Within the tray arcuate walls *c'* are arranged of the same height as the tray walls *b'*, and defined by radii which have the angular points of the tray as their centres. Suitably the radii of the arcuate walls *c'* are each about $\frac{1}{6}$ th of a diagonal of the tray *a'*. One end of each arcuate wall *c'* is spaced apart slightly by a gap *d'* from the adjacent tray wall; the said gap constituting an orifice to allow the passage of liquid. The other end of the arcuate wall *c'* is spaced apart from the adjacent tray wall about $\frac{1}{2}$ " or rather more, so forming a passage *e'* between the arcuate wall *c'* and the adjacent wall of the tray, thus harbours *e''* are formed. The passages *e'* are arranged towards the right hand ends of the arcuate wall as viewed from the latter's convex side. I also provide four sets of playing pieces, each set being coloured differently and comprising one boat *f'* and four fish *g'*. All the pieces are made of wood or other material such as celluloid which will float upon water.

The piece *f'* formed as the boat comprising a flat hull *h'* with a sharp bow, a straight stern, and an upright stern post *i'* in the centre of the stern. The width of the hull *h'* is such that it will just pass through the opening of a harbour *e''* with a very small allowance of room on each side. A vertical hole *j'* through the hull *h'* is formed at the bow. In the centre of the boat *f'* is arranged an upright flat member *k'* along the longitudinal axis of the boat to represent a sail. The first *g'* are each formed of a flat member with a forked tail *l'* and an upwardly projecting nose *m'* at the head. Four boat hooks or rods as illustrated in Fig. 6 are provided, one for each set of pieces.

In playing the game the tray *a'* is filled with a shallow layer of water and each player goes fishing in turn. That is to say the player places his boat *f'* in one of the harbours *e''* formed between the arcuate wall and the sides of the tray and also places his four fish *g'* in the centre of the water with the flat side on the water and the nose *m'* projecting upwards from the water. The player then takes his rod *o* and

inserts the downturned end of the rod through the hole *j'* in the boat. He then conducts the boat *f'* by means of the rod to the centre of the pond formed in the tray. He moves his boat so that the stern post *i'* lies just so near the upright nose *m'* of an adjacent fish *g'* that the surface tension of the water acting on the stern post *i'* and on the upright nose *m'* of the fish allows the fish to be drawn towards the boat until the stern post *i* of the boat and the nose *m'* of the fish are in conjunction. The player then by means of his rod conducts back through the narrow channel into the harbour the boat with the fish attached to it by surface tension.

Fig. 12 illustrates a board in which the game is played in a similar way to that described with reference to Figs. 7 to 11.

The skill consists in returning the boat through the channel without the fish becoming detached from the stern of the boat. It will be found that when the boat is fishing a sufficient surface tension arises to cause the fish to be attracted towards the adjacent boat. When the boat and the fish are being drawn through the harbour channel an opposing surface tension will be created by the narrow opening through which the boat is passing, which surface tension will tend to separate the boat and its following fish. When the player has succeeded in getting one fish through the harbour he then goes fishing for another and so on.

Boats and fish are suitably coloured different colours in the four different cases and the players draw lots as to the order in which they shall fish. If desired all the fish may be placed in the pond at one time and the fishermen may take it in turn to go fishing.

It will be evident that details of construction may be varied in many ways without departing from the scope of the invention.

I claim:

1. Game apparatus comprising a vessel containing liquid, a primary floating body of thin flat form with means at one end to be engaged by a manually actuated boat-hook or the like enabling the body to be drawn across the liquid, and having an upstanding portion at the other end of the primary floating body sufficiently high to accentuate surface tension at said other end to attract a second floating body, and one or more secondary floating bodies for adherence to the first by surface tension.

2. Game apparatus comprising a vessel containing liquid, a floating body of thin flat form with means at one end to be engaged by a manually actuated boat-hook or the like enabling the body to be drawn across the liquid, and having an upstanding portion at the other end of the floating body sufficiently high to accentuate surface tension at said other end to attract a second floating body, and a secondary floating body for adherence to the first by surface tension, the secondary body having an upstanding portion at one end subject to the action of surface tension thereon.

3. Game apparatus comprising a vessel for containing liquid, a thin flat body adapted to float upon liquid in said vessel and having means engageable by an actuating element for drawing said body across the liquid and a non-horizontal marginal surface of said body of sufficient area to accentuate surface tension at the latter surface with such liquid to attract a second floating body, and one or more secondary floating bodies for

adherence to the first mentioned body by surface tension.

4. Game apparatus according to claim 3, the said vessel comprising opposed walls defining a channel, one of said walls being movable to vary the width of the channel, thereby varying the effect of surface tension of floating bodies passing therethrough.

5. Game apparatus according to claim 3, the said vessel comprising opposed walls defining a channel, one of said walls being movable angularly with respect to the other wall to divergently vary the width of the channel, thereby varying the

effect of surface tension of floating bodies passing therethrough at different points along the channel.
